UNITED STATES PATENT OFFICE.

OSCAR VON MORSTEIN, OF BERLIN, GERMANY.

ELECTRIC GAS-IGNITER.

SPECIFICATION forming part of Letters Patent No. 669,543, dated March 12, 1901.

Application filed December 8, 1896. Serial No. 614,931. (No model.)

To all whom it may concern:

Be it known that I, OSCAR VON MORSTEIN, a subject of the King of Prussia, German Emperor, and a resident of the city of Berlin, in the Kingdom of Prussia, Germany, have invented certain new and useful Improvements in Devices for the Ignition of Gas-Jets by Means of Electricity, (for which I have obtained patents in Germany, No. 88,271, dated 10 October 19, 1895; in France, No. 254,819, dated March 17, 1896; in Belgium, No. 120,494, dated March 18, 1896, and in Great Britain, No. 20,801, dated November 4, 1895;) and I do hereby declare that the following is a full, 15 clear, and exact description of the invention, which will enable others skilled in the art to which it appertains to make and use the same.

This invention relates to devices for the ignition of gas-jets by means of electricity, said 20 devices being of the kind in which the gas-jets are at a distance from the operating-place.

The invention consists in a device for the electric ignition of gas-jets from a distance by means of secondary induction-currents, 25 for the purpose of which ignition the contact arrangement when set in activity keeps up an intermittent close-circuiting so long as is necessary.

It is known that illuminating-gas when left 30 unused for a length of time decomposes in the pipes, and some time passes before the in-combustible products of decomposition and the column of air that may be present between the gas-cock and the burner are ex-35 pelled by the outwardly-flowing combustible gas. Therefore in the devices hitherto known having for object the ignition of gas-jets from a distant point there exists the danger that after the gas-cock has been opened, whether 40 by hand or by means of an electromagnetic cock-opener, the contact will operate for too short a length of time, and consequently no ignition of the gas will take place, and that the non-observance of this circumstance, es-45 pecially when the lights are not visible from the position of the operator, may be the cause of gas-explosions and gas-poisoning. A fur-50 ther serious evil, certainly only met with in such devices as effect the ignition of the gas 55 by means of induction-currents, is that hitherto the interruptions of current requisite for the inductive action have been effected at the

inductor and by electrical means. The primary circuit then either receives through this electromagnetic circuit-breaking arrangement a resistance injurious to the inductive action or the magnetic attractive force at disposal remains so small that a perfectly sure action of the circuit-breaking arrangement is not obtainable or is deranged by the slightest 60 causes.

In the accompanying drawings, which illustrate the device of this invention for igniting gas-jets from a distance, Figure 1 is a view of a gas-pipe provided with burners to which the wires leading from the induction-bobbins are applied. Fig. 2 is a view of the contact mechanism with intermittently-closed circuit, and Fig. 3 shows a modification of said contact mechanism. Fig. 4 is a further modification thereof in connection with the lever for opening the gas-cock.

a is a gas-pipe fitted with several burners *b*, at which terminate the conducting-wires *c* of the secondary bobbins *S' S²*, which are 75 wound over a primary bobbin *P*. In the conductor *x* of the primary bobbin *P* is interposed the contact mechanism *C'*, which may be located at any suitable distance from the burners *b* and from the battery *B*. 80

Secondary induction-currents are used for igniting purposes. The induction-bobbins—one or more secondary bobbins *S' S²*, slid over primary bobbins *P*—may be located at any suitable distance from the burners *b*, the ends 85 of the wires of said secondary bobbins being led in a known way to the burners, where they terminate in igniting-points. The currents are conducted to the burners and effect ignition in the form of overspringing sparks. 90

The peculiarity of the device consists in that the contact-place *C* (*C' C² C³*)—that is to say, the place or places from which the gas is to be ignited—may be at any desired distance both from the induction-bobbins *S' S²* and 95 from the burners *b*, and accordingly the whole operative means is so designed that the same manipulation—say a single pull, pressure, or movement of a lever—establishes at the same time not only a contact of sufficiently-long 100 duration for the ignition of the gas, but also produces the requisite interruptions of current for the inductive action. Contact *C'* consists of a clockwork mechanism which for one

revolution of the ratchet-wheel s is released by lifting the pawl k out of said wheel and which, by the teeth of one of its wheels r , brings about an intermittent contact with the 5 contact-piece u . The clockwork may easily be combined with means for releasing the same every time it is wound up. When the pawl k is removed from the ratchet-wheel s , the clockwork rotates the wheel r , the teeth 10 of which during its rotation repeatedly establish the contact with the contact-piece u , and thus interrupt a like number of times the current passing from the battery B to the primary bobbin P . Each of such interruptions corresponds to a spark at the burners 15 generated by the induction-currents in the bobbins S' S^2 .

An extremely simple contact arrangement C^2 is shown in Fig. 3. It consists of a vibrating spring f , which, set in oscillation by hand, strikes against a contact-piece g . By correspondingly designing the length and thickness of the spring f and a weight at its end the desired duration and velocity of the oscillations may be obtained. Such or a similar contact device may also be so arranged that simultaneously with its action the gas-cock is opened. A device of this kind is shown in Fig. 4. The hand-lever by which the clock-work in the contact mechanism C' is released or by which the spring f in that of Fig. 2 is set in oscillation may be connected directly to the plug of the gas-cock. If at some part of the arrangement in question it should be 30 desired to actuate an electromagnetic gas-cock opener, the necessary close-circuiting

therefor can be effected by the same manipulation.

The details of construction of the contact device may be carried out in different ways— 40 for example, as indicated at C^2 . The spring f' , in being brought into the proper position relatively to the contact-piece g' , by moving a lever H , (the gas-cock lever, for instance) or the like, may also be set in oscillation by 45 causing it to impinge at the same time against a part h projecting in its path.

The condenser K is interposed in a known manner between the circuit-breaking points.

What I claim as my invention, and desire 50 to secure by Letters Patent, is—

A device for igniting gas-jets from a distance by means of secondary induction-currents, said device consisting of a source of the current and a primary bobbin over which the 55 conducting-wires terminating at the burners are wound as induction-bobbins and of a vibrating spring interposed in the conductor for the purpose of alternately closing and breaking the electric circuit during the time 60 of its oscillations which spring is so located at a distance from the contact-piece that it can only reach the latter in its oscillations, substantially as described and shown.

In testimony whereof I sign this specification in the presence of two subscribing witnesses.

OSCAR VON MORSTEIN.
